US00D991173S

(12) **United States Design Patent** (10) **Patent No.:** **US D991,173 S**
Huang et al. (45) **Date of Patent:** **** Jul. 4, 2023**

(54) **POWER SUPPLY**

(71) Applicant: **Changzhou Jutai Electronic Co., Ltd.**,
Jiangsu (CN)

(72) Inventors: **Wei Huang**, Jiangsu (CN); **Chengqian Pan**, Jiangsu (CN)

(73) Assignee: **Changzhou Jutai Electronic Co., Ltd.**,
Changzhou (CN)

(**) Term: **15 Years**

(21) Appl. No.: **29/771,173**

(22) Filed: **Feb. 19, 2021**

(51) **LOC (14) Cl.** **13-02**

(52) **U.S. Cl.**

USPC **D13/110**

Primary Examiner — George D. Kirschbaum

Assistant Examiner — Suzanne E Tisdell

(57) **CLAIM**

The ornamental design for a power supply, as shown and described.

DESCRIPTION

FIG. 1 is a front top perspective view of a power supply, showing a first embodiment of my new design;

FIG. 2 is a rear top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front top perspective view of a power supply, showing a second embodiment of my new design;

FIG. 10 is a rear top perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof; and,

FIG. 16 is a bottom plan view thereof.
